UNITED STATES PATENT OFFICE.

CLEMENT LEE DOWNEY, OF CINCINNATI, OHIO.

STACKING STEM FOR COIN-COUNTING MACHINES.

Application filed March 20, 1925. Serial No. 17,071.

My invention relates to machines in which a predetermined number of coins are automatically stacked in a coin package and formed into a roll containing a definite number of coins, and my invention particularly relates to the stacking stems in which these rolls of coins are stacked.

In machines of this character a definite number of coins are usually delivered to a 10 spout to which is attached a stacking stem of suitable diameter as required by the particular denomination of the coins to be counted. Into this tube is inserted the coin wrapper, to receive the coins, which is withdrawn when the proper number of coins have been delivered. It sometimes happens that the coins as they drop into the tube become jammed and fail to fall into the package. It also often happens that the coins in moving 20 in a vertical plane with reference to the stem strike the sides of the wrapper and stick. Then coins dropping one by one into a package have not enough weight to overcome a frictional engagement with the wrapper.

It is my object to provide means for holding back a predetermined number of coins and then projecting them sideways into the wrapper where the weight of the coins and their velocity in the stem will cause them 30 to fall rapidly into the wrapper.

Further it is my object to construct the stacking stems so that the operator may see while the coins are being delivered both that the coins are delivered properly from the machine in the correct number, and if any jamming of the coins has happened that correction may be made before the coins are deposited in the wrapper.

In the drawing:

40 Figure 1 is a perspective view of the coin tube.

Figure 2 is a longitudinal section of the tube along the lines 2—2 of Figure 1.

Figure 3 is a section along the lines 3—3 of 45 Figure 1.

There is shown generally indicated at 1, the main body portion of the device. In the particular stem shown a groove 2 is disposed in a flanged portion 3 in the top part of the 50 stem. A strap or clamp fits in this groove and thereby supports it in the discharge compartment of the coin filling machine, with the stem extending preferably down and outwardly from the machine in a diagonal direction. The method and the position of sup-

port is, however, immaterial inasmuch as it forms no part of this invention. The inner portion 4 of the stem tapers inwardly from the base 5, and the tubular wrapper 5^a is held at the top of this tapered portion. The upper portion of the stem tapers on its inner side more gradually than the base as shown at 6. At the bottom of the upper tapered portion the inner walls 7 of the tube extend straight down to the tapered portion of the walls at the base. Partway up in the cylindrical walls removed from the tapered portion of the base sufficiently to permit a drop of the coins into the wrapper is a slot 8 in which a shutter 9 is retained. A boss 10 extends out from the outer walls of the stem and a pin 11 retained in the boss is the pivot for the shutter 9. A spring 12 encircling the pin and attached at its upper end is hooked over the shutter to provide a tension to keep the shutter in position in the stem blocking the cylindrical aperture through it. The shutter extends through the slot opposite the boss and a bent over end 13 is adapted for a finger grip to open and close the shutter. Disposed in position in the walls of the stem with its center adjacent the base of the upper tapered portion is an aperture 14 of a size small enough to not permit a coin to fall out and through which an operator may clearly see the coins in the cylinder in case there is a stoppage in the upper tapered portion. In the walls of the stem adjacent the shutter another aperture 15 provides a peep hole through which the operator can see the coins on the shutter and if desired the coins in the top portion of the wrapper.

As noted these holes are preferably round, as shown, and of smaller size than the coin which is to be packed in it. Slots have been found to be impractical as the sides of the coins frequently catch in them and so block up the tube, or a coin might be discharged through a slot sufficiently long to give proper inspection. The eight openings further provide an opening through which any pointed instrument may be inserted to clear blocked coins from the tube.

It will be observed that as the stacking stem is preferably held diagonally from the machine and as the shutter moves from one side of the tube the coins will be tilted and fall diagonally into the wrapper. This tilting of the tube, the shutter releasing one side of the bottom coin first, and the distance

between the shutter and the position at the base in the tapered portion where the wrapper is held provides a stacking stem which will discharge almost instantaneously with the 5 removing of the shutter from the inside of the stem.

While this shutter feature is novel as regards a stacking stem, it is also new to provide peep holes located in several positions 10 in the stem for the insertion of a pointed object to clear the passage.

Having thus described my invention, what I claim as new and desire to secure by Letters Patent, is:—

15 1. A stacking stem for coins comprising a tubular member having a hollow cylindrical portion of sufficient size as to receive a stack of coins, said cylindrical portion being of smaller size than will accommodate a wrapper 20 for the coins, said cylindrical portion having a supporting shutter intermediate the ends thereof, and said cylindrical portion having an opening of sufficient size as to admit an

instrument to dislodge coins in the wall thereof adjacent the shutter.

2. A stacking stem for coins comprising a tubular member having a hollow cylindrical portion of sufficient size as to receive a stack of coins, said cylindrical portion being of smaller size than will accommodate a wrapper 30 for the coins, said cylindrical portion having a supporting shutter intermediate the ends thereof, and said cylindrical portion having an opening of sufficient size as to admit an instrument to dislodge coins in the wall thereof at the receiving end thereof.

3. A stacking stem for coins comprising a tubular member having a hollow cylindrical portion of sufficient size as to receive a stack of coins, said cylindrical portion being of smaller size than will accommodate a wrapper 40 for the coins, and said tubular member having a tapered portion adjacent an end of the cylindrical portion to guide a coin wrapper into receiving position.

CLEMENT LEE DOWNEY.
